W. F. CREMEAN.
BRAKE BEAM HANGER.
APPLICATION FILED APR. 3, 1918.

1,298,902.

Patented Apr. 1, 1919.

34 Inventor:
William F. Creneau,
by Parky Cook.
Atty.

UNITED STATES PATENT OFFICE.

WILLIAM F. CREMEAN, OF FRANKFORT, INDIANA.

BRAKE-BEAM HANGER.

1,298,902.

Specification of Letters Patent.

Patented Apr. 1, 1919.

Application filed April 3, 1918. Serial No. 226,399.

To all whom it may concern:

Be it known that I, WILLIAM F. CREMEAN, a citizen of the United States, residing at Frankfort, in the county of Clinton and 5 State of Indiana, have invented certain new and useful Improvements in Brake-Beam Hangers, of which the following is a specification.

My invention relates to a new and useful 10 improvement in brake beam hangers and particularly to a hanger that is so arranged that after the pin is placed through the hanger arms and the said hanger arms placed in their normal or set position it 15 will be impossible for the pin to work out or be lost from the hanger arms while the hanger is in service. As is well known a good many derailments are caused by the failing of the brake beam hangers, allowing 20 the brake beam and brake heads, etc., to drop on the track in front of the wheels.

An object therefore of my invention is to provide a brake beam hanger that will be simple in construction and so arranged 25 that the hanger arms are locked in position by a special form of pin and bracket and when the said hanger is in its set position it is impossible for the pin to become disengaged or to work out of the said hanger 30 arms.

Another object of my invention is to so construct the brake hanger that it may be quickly assembled, or on the other hand may be quickly taken down or apart if so 35 desired.

With these and other objects in view, my invention consists of certain new and novel arrangements and combination of parts as will be hereinafter more fully described and 40 pointed out in the claims.

In the drawings:

Figure 1 is a side elevation of my improved hanger as attached to a standard M. C. B. brake head;

Fig. 2 is a front elevation of the hanger and part of the bracket;

Fig. 3 is a front elevation of a modified form;

Fig. 4 is a plan view of one arm of the 50 hanger arm of the modified form; and

Fig. 5 is a view of the opposite hanger arm.

Referring now to the drawings, an ordinary standard brake head 1 is shown, which 55 is secured to the brake beam 2, which beam

is supported by my improved hanger 3, and the upper end of said hanger is pivotally secured to the bracket 4, which bracket may be secured to any part of the pedestal or truck as desired.

60

Referring now to the form of hanger shown in Fig. 2, it will be seen that it consists of a substantially U-shaped member having the two side arms 5 and 6 and the integral lower arm 7. The upper ends of 65 the arms 5 and 6 are enlarged as at 8 and 9, and are provided with the seats 10 and 11 located centrally thereof and on the inner portion of said enlarged portions 8 and 9. Provided on the inner surfaces of the two 70 arms 5 and 6 and at a slight distance below the enlarged portions 8 and 9 are the two outstanding upwardly bent lugs 12 and 13.

Referring now to the bracket 4 it will be seen that the cross piece 14 has to be of 75 a certain design, that is, it must be provided with the downwardly extending lips 15 near its opposite ends. The remaining portion of the bracket may be of any form desired. The purpose of these downwardly 80 extending lips 15 and the upwardly extending lugs 12 and 13 is; that after the pin 16 is placed in the seat 10 formed in the enlarged head portion 8 and passed through the longitudinally extending opening 17 in 85

the bracket arm 14, the arms 5 and 6 are sprung slightly apart and held in an upright position, that is in a position that will be parallel to the tracks, and allow the enlarged head portion 9 to spring over the 90 opposite end of the pin 16 so that the ends of the pin rest in the seats 10 and 11, and the arms 5 and 6 may then be swung downwardly and the lugs 12 and 13 pass behind the downwardly extending lips 15 of the 95 bracket 4 to prevent the arms 5 and 6 from being forced outwardly, making it impossible for the pin 16 to become dislodged from the seats 10 and 11 formed in the enlarged portions 8 and 9.

100

The brake head may then be positioned over the arm 7, completing the hanger arrangement.

The brake hanger, of course, will pivotally support the brake beam and if it is 105 desired to remove the same it is only necessary to swing the entire hanger upwardly until the lugs 12 and 13 pass in front of the downwardly extending lips 15, when the arms 5 and 6 may again be sprung apart 110

slightly until the pin becomes disengaged from one of the seats, and one of the arms slightly shifted so that the pin may again be removed.

- 5 Referring now to the other form shown in Figs. 3, 4, and 5, it will be seen that in this instance instead of having the arms 18 and 19 formed integral, they are two separate structures, and slightly different with 10 regard to each other. Referring first to the arm 18, it will be seen that it is also provided with an enlarged upper end 20 which is provided with a rectangular seat 21 and an opening 22 registering with said seat. 15 Also formed directly above the seat 21 is a cap portion 23 which extends outwardly and downwardly beyond the upper edge of the seat 21. The purpose of this cap portion is that the pin 24 may be angularly held with 20 regard to the arm 18 and then passed through the opening 22 and the rectangular head 25 of the pin be placed in the rectangular seat 21. From this it will be seen that the pin 24 can not be removed from the arm 18 unless 25 the same is first tilted upwardly so that the head 25 can pass under the downwardly projecting cap portion 23. This arm 18 is also provided with the upwardly extending lug 26 similar to the lug 12 in the first mentioned form of hanger.

Near the lower end of this hanger arm 18 is also an enlarged recessed portion 27 and an opening 28 registering therewith so that a second pin 29 may be passed through 35 the opening 28 and the head 30 of the pin 29 tightly fit within the recessed portion 27.

Referring now to the opposite arm 19, this has an opening 31 near its upper end and upwardly extending lug 32 similar to the 40 lug 26 and a further opening 33 near its lower end. The opening 33 also has the slight keyway 34 as clearly shown in Fig. 5. The pin 29 at its end is provided with the outwardly extending lug 35 to clamp against 45 the outer surface of the arm 19 as will be shortly explained. The cross arm 36 of the bracket is similar to the cross arm 14 of the bracket 4, and is provided with the downwardly extending lips 37 similar to the 50 lips 15.

The assembling of this bracket is as follows: First the pin 24 is passed through the opening 22 in the arm 18 which is made possible by tilting the said pin in an upward 55 direction until the head 25 passes under the cap portion 23. When its head is seated in the recessed portion 21 the bracket arm 18 is held in a horizontal position so that the lug 26 may pass in front of the lip 37 so that the lug 26 will be behind the lip 37 and the pin 24 may pass through the opening 38 in the bracket arm 36. The arm 19 is then held in an upright position, that is parallel with the ground and the pin 24 passed through the 60 opening 31 in said arm. The arm is then

allowed to drop so that the lug 32 will pass behind the lip 37. Both arms are now in a vertical position and the lower ends of said arms are forced slightly toward each other which is made possible by having the openings 31 and 22 of greater diameter than the diameter of the pin 24. The pin 29 is then passed first through the opening 28 but not so far that the head 30 will be engaged in the recess 27. The pin 29 is then turned 70 until the lug 35 passes through the keyway 34 and is then turned until the lug 35 will be at right angles to the bracket arm 19, when the arms 18 and 19 are again forced outwardly so that the head 30 will now fit 75 tightly within the recessed portion 27. The brake head is then passed through the said hanger and of course after it is once in position it will be impossible for the lower ends of the arms 18 and 19 to be forced toward 80 each other, so that it is impossible for the pin 29 to work out or become disengaged from the two said arms 18 and 19.

If it is desired to remove the hanger the brake head will first have to be removed and the arms 18 and 19 swung inwardly and the pin 29 turned so that the lug 35 will pass through the opening 34 and the arms may then be swung upwardly as previously mentioned and the upper pin disengaged.

From the foregoing it will be seen that with either form of the brake hanger shown it will be impossible for the pins to become accidentally lost thereby preventing the brake beam from dropping beyond its normal position. At the same time the hanger arms may be renewed or the pins renewed by operating the hangers as heretofore described.

The hanger is one that is relatively cheap to manufacture, having but few parts and necessitating no great care after the same is once set up in position.

Having thus described my invention, what I claim as new and desire to secure by Letters Patent is:

1. A brake beam hanger comprising two hanger arms and means connecting said hanger arms at their lower ends, a bracket provided with downwardly extending lips, a pin carried by the bracket and engaging the arms and means carried by the arms and disposed behind said lips for retaining the hanger arms in position when said hanger arms are in their normal set position.

2. A brake beam hanger comprising two hanger arms and means connecting the lower ends of said arms, upwardly extending lugs on the inner surface of said arms and arranged near the upper portion thereof, a bracket provided with downwardly extending lips and the said lugs extending behind the said lips when the said arms are in a suspended vertical position and a pin carried by the bracket and engaging the arms.

3. A brake beam hanger comprising two hanger arms and means connecting the lower ends of said hanger arms, a bracket arm provided with downwardly extending lips and lugs formed on the inner surface of said arms and near their upper portion adapted to pass behind said lips when the hanger arms are in a vertical position, and a pin engaging the upper ends of said arms, the parts being so arranged that said pin is prevented from being removed from said arms when said arms are in a suspended vertical position.

4. A brake beam hanger comprising two hanger arms and means connecting the lower ends of said hanger arms, a bracket arm provided with downwardly extending lips, and lugs formed on the inner surface of said hanger arms, said arms adapted to assume a horizontal position when being removed and adapted to be swung downwardly to a vertical position so that the said lugs will pass behind the said lips to prevent the said arms from moving away from each other, and means connecting the upper ends of said arms and adapted to be placed in position when the arms are in their horizontal position and said means being held from removal when the arms are in a suspended vertical position.

5. A brake beam hanger comprising two hanger arms and upwardly extending lugs formed near the upper ends of said arms and on the inner surface thereof, a cap portion extending over one of said openings, and a pin adapted to pass through said opening provided with the cap portion when said pin is held in an angular position with regard to said arm, a bracket arm provided with two downwardly extending lip portions and the aforementioned lugs on said hanger arms adapted to swing behind said lips when said arms are in a suspended vertical position, and a second pin passing through openings in the lower portions of

said arms, and means for preventing said pin from being disengaged from said arms.

6. A brake beam hanger comprising two hanger arms provided with upwardly extending lug portions on the inner surfaces of said arms, a bracket provided with downwardly extending lips and said lugs adapted to extend behind said lips when said arms are in a suspended vertical position, a recessed portion in the upper end of one of said arms and provided with a cap extending partly over said recessed portion, and a pin adapted to be angularly held with regard to said arm when it is to be inserted, and said cap portion preventing said pin from being removed unless said pin is held in an angular position, openings formed in the lower ends of said arms and one of said openings provided with a recessed portion registering therewith, and a pin adapted to pass through the openings in the lower ends of said arms when said pin is held in a certain position and the lower ends of said arms are forced inwardly, and said pin to be rotated and to lock said arms when said arms are again forced outwardly.

7. A brake beam hanger comprising two hanger arms and a bracket coöperating with said arms to hold said arms in their set position when said arms are in a suspended vertical position, the lower ends of said arms adapted to be swung inwardly, and means connecting said arms and to lock said arms when the lower ends of said arms are again forced outwardly.

8. A brake beam hanger comprising in part a hanger arm provided with an opening adapted to receive a pin and a recessed portion registering with said opening and adapted to receive the head of the pin and an outwardly and downwardly extending cap disposed over a part of said recessed portion.

In testimony whereof I affix my signature.
WILLIAM F. CREMEAN.
